SHOPPING CART

Robert E. Moran, 615 Bedford Road, Schenectady, N.Y.

Filed Oct. 28, 1963, Ser. No. 77,170

Term of patent 14 years

(Cl. D14—3)

FIG. 1

FIG. 3

FIG. 2

FIG. 4

FIG. 5

FIG. 6

FIG. 1 is a rear perspective view of a shopping cart showing my new design;

FIG. 2 is a side elevational view thereof;

FIG. 3 is a top view thereof;

FIG. 4 is a bottom view thereof;

FIG. 5 is a front view thereof; and

FIG. 6 is a rear view thereof.

I claim:

The ornamental design for a shopping cart, as shown.
